TOY GUN

Hearl D. Jones, 114 N. 29th St., and Paul E. Snider,
2616 Alanmede Road, both of Louisville, Ky.
Filed Aug. 1, 1962, Ser. No. 214,108
2 Claims. (Cl. 273—101.2)

This invention relates to toys, and more particularly, to toy guns.

The principal object of the present invention is to provide a toy gun for small children which is absolutely safe under all circumstances of play, and, at the same time, possesses the novel appeal to adventure that simulated firearms always connote.

The body of the gun and most of its component parts can be advantageously manufactured from plastic or a similar material.

Another object of the present invention is to provide a toy gun comprising a minimum number of working parts. It will, consequently, lend itself to the most inexpensive cost of production. The simplicity of design ensures its durability in play-time fun. In design, the target, traced on a thin sheet of clear plastic, and moved laterally by pivoting the forearm of the gun, is never out of sight of the young marksman. He can, however, miss the target by failure to center the target accurately before firing. Another plastic sheet carries only a projectile "spot" which pivots from a horizontal position when in firing position, to a vertical plane when in "fired" position. Too, the present invention features a scope, which may be a "dummy" with no magnification whatever.

Another unique feature of the present invention is that, upon firing, the target position is automatically locked in place; a tooth on the forward side of the visual-projectile assembly registers with one notch in a toothed series mounted radially on the rear extremity of the target mechanism. Thereby, upon firing, each marksman can "show" his rivals just where he hit. The target will not move until the gun is re-loaded.

In the accompanying drawing, several embodiments of the invention are shown:

FIGURE 1 is a vertical sectional elevation showing the trigger assembly, the visual-projectile assembly, the target assembly, and the scope.

FIGURE 2 is a sectional plan view showing the visual-projectile assembly in "fired" position, the unique method of locking the target in "fired" position, and the pivoting forearm which moves the target.

FIGURE 3 is a partial sectional elevation showing the curved transparent target sheet. It shows, too, the relative positions of the target sheet and the projectile sheet in "fired" position. This view also shows the loading bolt, which is made monolithic with the visual-projectile (loading) assembly.

FIGURE 4 is a rear sectional elevation showing the scope, and, therein, the target, the visual-projectile "spot," and the tooth and notch method of locking the target in "fired" position.

Referring to the drawing, wherein like numerals indicate like parts, it can be seen that, in operation, the bolt 15 is pulled down until the projection 16, on the projectile assembly, impinges on the underneath side of the sear 18 on the trigger assembly, at which time the spring 22 is in tension. The gun is now in firing position. To fire, the trigger 17 is pulled, at which time the projection

2

16 is released, spring 22 is activated, and, at once, the visual-projectile assembly 11, including the bolt 15, the projectile sheet 12, the projectile "spot" 13, the lock tooth 14, is pivoted about the bolt 20. This returns the visual-projectile assembly to "fired" position.

During firing, the target sheet 7, with the target superimposed thereon, is pivoted about the retaining ring 9 by turning the forestock to right or left (at the discretion of the young marksman). The target sheet 7 is rigid on the projection 6 of the pivotal target assembly. The teeth (notches) 8 also on the projection 6, serve to lock the target assembly in "fired" position by registration of the tooth 14, rigid on the front of the visual-projectile body 11. Please note that the trigger return spring 21 returns the trigger assembly 17 and 18 (monolithic), pivoting it about the bolt 19.

Please note that in FIGURE 2, the forward section of the scope 3 is expanded to accommodate the lateral movement of the target sheet, which could contain a number 20 of small targets. FIGURE 4.

Please note that, in firing, nothing ever leaves the barrel 2 of the gun. Looking through the scope, the child will see the target in open view in simulated natural surroundings. Upon firing, he will observe the projectile "spot" 25 register a direct hit or score a near-miss before his very eyes. The projectile "spot" popping into superimposition on the target backdrop, looks amazingly realistic, it hardly seems possible that it is merely a spot on a transparent sheet of plastic. The only function of the pivotal 30 forearm 5, contained by the rear barrel 2, is to move the target sheet across the scope's field of view. This gives the illusion of a naturally moving target. The stock 1, not fully developed in the drawing, is of conventional design.

35 While the foregoing description sets forth the invention in specific terms, it is to be understood that numerous changes in shape, size, and materials may be resorted to without departing from the spirit and scope of the invention as claimed hereinafter.

40 Having thus described our invention, we claim as new and desire to secure by Letters Patent:

1. In a toy gun, a visual-projectile assembly, a scope expanded through its mid-section to accommodate the lateral movement of a self-contained moving target, said 45 visual-projectile assembly comprising a sheet of transparent plastic, said sheet containing a "spot," said sheet so mounted as to pivot from a horizontal position to a vertical position through a plane containing the longitudinal plane of said scope, said plastic sheet held in a 50 horizontal position by the gun's trigger assembly, and, when released (fired), springing into a vertical position whereupon said "spot" is visible through said scope, and superimposed therein on said moving target; said self-contained moving target comprising a pivotal forestock, 55 said forestock pivoting through a horizontal plane about a retaining ring mounted in the body of the gun proper, said forestock offset upper and projecting into the body of the gun to the rear of the pivot point, the rear end of said projecting forestock carrying a curved sheet of 60 transparent plastic, said plastic sheet mounted in a vertical plane perpendicular to the plane of said pivotal forestock, said plastic sheet bearing the image of an animal which is the gun's self-contained moving target; the forward end of said pivotal forestock serving as a normal support 65 for the gun and also as a means of moving said target by pivoting said forestock to right or left.

2. A toy gun as recited in claim 1, said pivotal forestock expanded on its rearward extremity into a lateral arc, said arc bearing a set of "V" teeth, said "V" teeth positioned beneath said plastic target sheet said "V" teeth notched in a vertical plane, said arc extending the full length of said curved plastic sheet; said visual projectile assembly containing a "V" tooth, said tooth positioned beneath said plastic sheet containing said "spot" so that when in a "fired" position, said tooth registers with a notch in the aforesaid arc of said pivotal forestock, thereby locking said pivotal forestock, and said target sheet in that position.
